UNITED STATES PATENT OFFICE.

CHARLES F. REULEKE, OF PHILADELPHIA, PENNSYLVANIA.

HAT PROTECTOR.

Application filed September 3, 1926. Serial No. 133,339.

The main object of this invention is to provide a hat protector suitable for protecting wearers during inclement, stormy and rainy weather. For this object, the provision of an entire covering for the crown and the brim of a hat and means on said protector for the draining the rain dripping upon the surface of the covering rearwardly so that the water will fall from the edge 10 of the brim at the rim of the hat, is made.

Another object is to provide a hat protector covering the crown and brim of the hat provided with a ridge extending partially around the circumferential edge of the hat which guides the rain falling upon the brim covering rearwardly so that it falls from the rear edge of the hat, and does not interfere with the vision of the wearer.

The above and other objects will become apparent in the description below, in which characters of reference refer to like-named parts in the drawing.

Referring briefly to the drawing, Figure 1 is a perspective view of the hat protector.

Figure 2 is a top plan view of the same.

Figure 3 is a sectional elevational view taken on line 3—3 of Figure 2.

Referring in detail to the drawing, the numeral 10 indicates the roof of the crown which surmounts the crown wall 11 of the hat. This roof and wall constitute the crown of the hat and the latter is encircled by a relatively wide brim 12 and the outline described and illustrated in Figure 3, is of the well known stiff straw hat which when subjected to the rain or storm, or the like would lose its shape and become unwearable.

To guard against the elements, a hat protector is provided which comprises the flat oval shaped piece of flexible material 13, which is joined to the roof. This marginal edge is joined to an encircling wall 14, which extends downwardly and covers the crown wall 11, of the straw hat.

The encircling plate 15 formed of the same material as the hat protector, covers the upper surface of the brim 12 of the hat and has extending therefrom a lip 16 which projects in a plane parallel to the plate 15 immediately beneath it. The forward portion of the plate 15 is provided with a tapering rib 17 which extends approximately three quarters around the plate. Additional tail ribs 18 extend from the extremities of the main encircling ribs 17 and project to

ward the central portion of the surface of the plate 15. This rib is triangular in shape, and has a sloping surface 19 inclined toward the center of the hat protector. The plate 60 15 is provided with the radial ribs 20 and 21 which extend from the encircling rib 17 toward the center of the hat. These radial ribs 20 and 21 extend over the greater portion of the width of the plate 15, and beyond 65 the extremities of these radial ribs, the channels 22 are formed thru which any rain which drops upon the surface 5 in the sector between the ribs 20 and 21 passes.

The protector is applied to the straw hat 70 by slipping the roof 13 and the encircling wall 14 over the crown of the straw hat. Hats of this variety are usually worn in an inclined position tilted rearwardly with the rear portion of the hat in the lowest plane. 75 As rain begins to fall upon the hat and upon the inclined surface 19 of the ribs 17, it begins gradually to circulate rearwardly and is deflected by the radial ribs 18 toward the longitudinal axis of the hat at the rear, and 80 thru the space between the rail ribs. The hat is divided into two sectors and the forward sector being that portion of the surface which exists between the ribs 20 and 21 85 formed at the front portion of the hat protector.

Any rain which drips in this sector is guided by the inclined surface of the encircling rib toward the sector of the hat and ribs 20 and 21 deflect this rain toward the 90 channels 22, from the front to the rear of the hat and eventually passes thru the passages to trickle from the edge.

It is to be noted that certain changes in form and construction may be made without 95 departing from the spirit and scope of the invention.

I claim:

1. A hat protector comprising a roof member and an encircling wall joined to the marginal edge of said roof member for covering the crown of the hat, an encircling plate joined to the encircling wall, said plate and roof member being parallel, an encircling rib mounted on the upper surface of said 100 plate covering the brim of the hat, said encircling rib bounding approximately three quarters of the forward edge of the hat symmetrically on both sides, and tail ribs 105 extending from the extremity of said encircling rib toward the center of the width of the hat in a rearward direction.

2. A hat protector comprising a roof member and an encircling wall joined to the marginal edge of said roof member for covering the crown of the hat, an encircling plate joined to the encircling wall, said plate and roof member being parallel, an encircling rib mounted on the upper surface of said plate covering the brim of the hat, said encircling rib bounding approximately three quarters of the forward edge of the hat symmetrically on both sides, tail ribs extending from the extremity of said encircling rib toward the center of the width of the hat in a rearward direction, said encircling and

tail ribs having inclined surfaces extending 15 toward the axis of said hat protector, the radial ribs extending partly across the width of the plate member dividing said plate member into sectors, said rib members forming a deflecting element for guiding the rain 20 toward the encircling wall of the hat protector, and channels between the ends of the radial ribs and surface of the encircling wall forming passage for the circulation of rain from one sector to another. 25

In testimony whereof I affix my signature.

CHARLES F. REULEKE.
